UNITED STATES PATENT OFFICE.

ERNST ANHEUSER, OF RACINE, WISCONSIN.

TOOL.

1,379,737.

Specification of Letters Patent. Patented May 31, 1921.

Application filed December 1, 1919. Serial No. 341,569.

To all whom it may concern:

Be it known that I, ERNST ANHEUSER, a citizen of the United States, and resident of Racine, in the county of Racine and State of 5 Wisconsin, have invented new and useful Improvements in Tools, of which the following is a description, reference being had to the accompanying drawings, which are a part of this specification.

10 The present invention relates to certain new and useful improvements in rotary rasps.

Rotary rasps are generally used in combination with a wire brush by mounting the 15 brush on one end of a driven shaft and the rasp on the other end thereof. Heretofore it has been common practice to make the rasps out of a solid piece of steel which has proven very unsatisfactory as the driven 20 shaft is unbalanced, the wire wheel weighing about $4\frac{1}{2}$ pounds, whereas the solid steel rasp weighs approximately 18 to 20 pounds.

Hence with the above and other inherent 25 objections in mind, my invention has for one of its objects to provide a rotary rasp which will be so constructed as to be extremely light in weight and to evenly balance with the usual wire brush or the like generally employed in combination therewith.

30 Another objection to the solid form of rotary rasp is that the same is very expensive as when the teeth become dull it is necessary to buy an entirely new tool. Therefore, my invention has for another of its 35 objects to provide a rotary rasp in which the rasp proper is carried by a holder and is capable of ready removal.

A further object of this invention is to 40 provide a rotary rasp formed from tubular material and having a holder for securing the same upon a driven shaft.

With the above and other objects in view 45 which will appear as the description proceeds, my invention resides in the novel construction, combination and arrangement of parts, substantially as hereinafter described and more particularly defined by the appended claims, it being understood that such changes in the precise embodiment of the 50 hereindisclosed invention may be made as come within the scope of the claims.

In the accompanying drawing I have 55 illustrated one complete example of the physical embodiment of my invention con-

structed according to the best mode I have so far devised for the practical application of the principles thereof, and in which:

Figure 1 is a plan view of my novel form of rasp illustrating the same as arranged on a driven shaft with a rotary wire brush. 60

Fig. 2 is an enlarged view of my novel form of rasp detached, said view having parts broken away and in section to more clearly illustrate its details of construction, 65 and

Fig. 3 is an enlarged fragmentary sectional view taken through a portion of my novel form of rasp on the line 3-3 of Fig. 2 to illustrate the novel form of cutting teeth I provide. 70

Referring now more particularly to the accompanying drawing, the numeral 5 designates a machine standard having a shaft 6 journaled in the upper end thereof, which shaft is rotated by means of a motor direct therewith or by means of a driven belt 7. While in Fig. 1 I have shown my novel form of rotary rasp as fixed to one end of the shaft 6, to the other end of which is fixed a wire brush or the like 8, it will be understood that my invention is readily capable of use alone, but it being common practice in the art to mount a wire brush or the like on one end of the driven shaft and a 75 rotary rasp on the other. 80

85 My novel form of rotary rasp consists of a tubular member or ring 9 having a plurality of cutting teeth 10 formed thereon by gouging the periphery thereof as at 11, see 90 Fig. 3. The ring member 9 is formed from ordinary steel tubing and hardened, as will be later described. The teeth 10 are arranged in staggered relation as best shown in Fig. 2 so that material cut thereby will 95 work to one side through the alined staggered channels formed therebetween as will be seen by reference to Fig. 2.

The rasp proper is detachably mounted upon a holder whereby the same may be renewed when the cutting teeth 10 thereof have become worn or broken. The novel holder which I employ consists of two complementary flange members 12 having hub members 13 formed centrally therein and provided with axially alined bores 14 for engagement by the drive shaft 6 or the like and each having a peripheral rim 15 for telescoping engagement with the adjacent 100 105

ends of the ring or rasp proper, as best shown in Fig. 2.

The flange members 12 have a plurality of spaced apertures 16 therein adapted to be brought into alinement to receive suitable binding or securing members 17 for holding the members 12 together and binding the rasp member therebetween. The telescoping engagement of the members 12 with the rasp member is limited by means of a laterally extending annular rib 18 formed on each member 12 adjacent its outer peripheral edge, the ribs 18 binding against the edges of the rasp member, as best shown in Fig. 2.

From the foregoing description taken in connection with the accompanying drawing, it will be at once apparent to those skilled in the art to which an invention of this kind appertains that I provide a rotary rasp for the purpose described which will be extremely light in weight when compared to the old type of rotary rasp, which will be readily renewable when the cutting teeth thereof have become worn and lost their cutting qualities and which will be practical for the purpose described.

What I claim for invention is:

1. A tool comprising a one-piece annular

tubular member formed from a length of pipe, cutting teeth stuck up from the outer peripheral surface thereof, and a holder for said member.

2. A tool comprising a one-piece ring-shaped rasp member, and a holder for said rasp member and engageable with the edges thereof.

3. A tool comprising two complementary flange members, a tubular rasp member having a snug engagement over portions of said flange members, and means for securing said flange members together to secure the rasp member thereon.

4. A rotary tool comprising two complementary flange members, an annular rib formed on each flange member adjacent its outer peripheral edge, a tubular rasp member engageable over the inner portion of the periphery of each flange member, said annular ribs limiting this telescoping engagement of the rasp member over the flange members, and means for drawing the flange members toward each other to secure the rasp member thereon.

In testimony whereof, I affix my signature.

ERNST ANHEUSER.
